UNITED STATES PATENT OFFICE.

ALBIN E. ANDERSON, OF OAKMONT, PENNSYLVANIA, ASSIGNOR TO PITTSBURGH
WIRE ROPE COMPANY, OF VERONA, PENNSYLVANIA, A CORPORATION OF
PENNSYLVANIA.

MACHINE FOR MAKING WIRE ROPE.

1,378,932.

Specification of Letters Patent.

Patented May 24, 1921.

Application filed February 25, 1920. Serial No. 361,165.

To all whom it may concern:

Be it known that I, ALBIN E. ANDERSON, a citizen of the United States, and resident of Oakmont, in the county of Allegheny and State of Pennsylvania, have invented a new and useful Improvement in Machines for Making Wire Rope; and I do hereby declare the following to be a full, clear, and exact description thereof.

10 My invention relates to the manufacture of wire ropes and cables, and it has for one of its objects to provide a machine of the character indicated which shall be simple in construction, and which shall occupy a 15 smaller floor space and require less driving power than machines which have heretofore been used for the same purpose.

Another object of my invention is to provide a machine for making wire ropes and cables which shall operate to lay up the wires forming the rope or cable without twisting the wires during their travel from the bobbins to the wire-laying mechanism.

With these objects in view, my invention 25 consists in a construction and arrangement of parts, one form of which is illustrated in the accompanying drawings, wherein Figure 1 is a side elevational view; Fig. 2 is a plan view of the structure shown in Fig. 1; Fig. 3 30 is a side view, partly in elevation and partly in section, showing the mechanism for assembling and laying the wires; Fig. 4 is an end elevational view of the flier frame and its supporting cradle; Fig. 5 is a front elevational view of one of the spiders composing the flier-frame; Fig. 6 is a fragmentary elevational view of a portion of the spider shown in Fig. 5, showing a device for locking the wire bobbins in position; and Fig. 7 35 is a longitudinal view of a wire bobbin suitable for use in my machine.

Machines for making wire rope, as heretofore constructed, have consisted of a rotary frame within which a number of wire-carrying bobbins were supported with their axes perpendicular to the axis of rotation of the frame, each bobbin being carried in a bracket or other support disposed within the rotating frame, but prevented from 45 rotating with the frame. This arrangement has two principal disadvantages. First, the brackets or frames, which are necessary to support the wire bobbins, occupy a considerable amount of space; and second, the wire 50 taken from each bobbin is twisted several

times by the rotation of the flier-frame before it is laid up with the other wires to form the rope. This twisting impairs the strength of the wires, and consequently of the rope, and the ropes so produced are 60 never perfectly straight, but are always bent at short intervals on account of the twisting of the component wires. On account of the bent and twisted nature of the product, machines of this class are commonly termed 65 "snake machines."

According to my present invention, I obviate both of the disadvantages mentioned above by mounting the wire spools with their axes all disposed in a line coinciding 70 with the axis of the flier-frame, and by reducing to a minimum the number of bends to which the wire is subjected between the spool and the finished rope. At first thought, it would seem that the machine 75 would be lengthened by arranging the wire spools with their axes lengthwise of the machine, instead of crosswise, but such is not the case, because the lengthwise arrangement, as in my present machine, does away 80 with the frames for supporting the spools, and makes it possible to attach the spools directly to the spiders which compose the flier-frame. In addition, the twisting of the wires between the bobbins and the rope is 85 entirely prevented, each wire being drawn from its bobbin at the speed and in the direction required.

For a more detailed description of my invention, reference may now be had to Figs. 90 1 and 2 of the drawing, which show the general construction of a machine consisting of a rotary flier-frame A, a twister-head or plate B, a drawing drum C, and a reel D for winding up the finished rope. Power for 85 driving the several rotary parts of the machine is derived from a suitable source, not shown, through a belt 2 which drives a pulley 3 secured to a horizontal shaft 4 which carries the flier-frame A and the twister-head B. Secured to the shaft 4 is a spur gear-wheel 5 meshing with a pinion 6 which, in turn, drives a spur gear-wheel 7 carried by the rear end of a countershaft 8 that extends beneath the flier-frame and carries at 100 its forward end a bevel pinion 9. The bevel pinion 9 meshes with a bevel gear-wheel 10 secured to a stub-shaft 11 which also carries a spur gear-wheel 12 that drives a set of reducing gears 13, 14, 15 and 16, the latter 110

gear being secured to a horizontal shaft 17 which carries the drawing drum C. The shaft 17 also carries a pulley 18 which is connected by means of a belt 19 to a pulley 20 on a shaft 21 upon which is mounted the winding reel D.

The flier-frame A consists of a number of circular spiders 25 connected together by means of parallel rods 26, which, as shown, 10 are three in number, although a larger number of connecting rods may be used if desired.

Each of the spiders 25 rests upon a pair of anti-friction rollers 27 that are supported 15 in bearings in the standards 28. Certain of the standards 28 carry yokes 29, at the top of which are supported anti-friction rollers 30 for the purpose of preventing upward movement of the frame which might occur 20 during rapid rotation.

Each of the spiders 25 carries a pair of bearings 31 for supporting the squared end of bars 32, upon the circular intermediate portion of which are mounted wire-carrying 25 bobbins 33, as shown in Fig. 7. Each of the bars 32 is preferably provided with a collar 34, near one end, for properly positioning the bobbin 33.

In order to fasten the bars 32 and the 30 spools 33 firmly but releasably in the bearings 31, I provide a device which is shown in detail in Figs. 3 and 6, and which consists of a bracket 35 secured to one of the three radial arms 36 of the spider 5, and 35 having inwardly extending projections 37 which coöperate with projections 38 on the bearing 31 to receive a key 39 provided with a depression in which is received a locking pin 40 that is pressed into the depression by 40 means of a helical spring 41. It will be evident that each wire bobbin may be readily removed from the machine by raising the pins 40 from the keys 39, removing the keys, and lifting the bar 32 from the bearings 31.

In order to prevent the spools 33 from 45 over-running during the operation of the machine, I provide each bobbin with a brake which consists of a strip of spring-metal 43 bolted to one of the arms of the adjacent 50 spider and exerting a yielding pressure on the flange of the bobbin.

The wire for each of the spools 33 is led around a small sheave 45 carried by one of the rods 26, each of these sheaves being carried 55 in a support 46 which is clamped to the rod 26, as shown in Fig. 5.

From the first sheave 45 each wire is led 60 forward to a point opposite to the first wire-bobbin where it passes over a second sheave 47 and thence to the twister-head B. Fig. 4 shows the arrangement of sheaves 47 for a machine that operates upon seven strands of wire, and it will be observed that the sheaves 47, like the sheaves 45, are carried 65 by suitable supports 48 secured to the rods

26. The strand from the bobbin nearest the front of the machine follows a somewhat different course, since this strand is to form the core of the rope and may consist of either wire or cord, according to the kind of wire 70 rope that is being made. It is led from one of the sheaves 47 to a sheave 49, as shown in Figs. 1 and 3, and thence through a central opening 50 in the twister-head B. This twister-head consists of a shaft 51 secured 75 in any convenient manner to the forward spider 5 to rotate co-axially therewith, and carrying the sheave 49 and a plate consisting of two parts 52 and 53 which are provided with a series of registering openings 80 54 through which the wire strands are passed. In each of the openings 54 is disposed an anti-friction roller 55. The construction of this twister-head forms the subject of my co-pending application for Letters Patent, Serial No. 361,166 filed February 25, 1920.

After passing through the twister-head B the wires are led through a spring-pressed clamp 56 and thence around the winding drum C and the reel D, the clamp, winding drum and reel being such as are commonly employed in this art, and therefore not being described in detail.

In the operation of my machine, the bobbins of wire having been placed in position and the wires led forward in the manner indicated above, the machine is started and the flier-frame A is rotated at high speed. During such rotation, each of the wire bobbins is free to rotate in response to the pull of the wire, the wires being maintained under tension by means of the brakes 43. It will be observed that each wire is unwrapped from its bobbin and led forward to the 100 twister-head without its being twisted in transit, and that each wire changes direction only twice before it reaches the final twisting mechanism. This reduction in the number of bends to which the wire is subjected 105 makes it possible to drive the machine with materially less power than has heretofore been necessary in machines of this kind. For the same reason, and also because the wires are not twisted on their way to the final 110 twisting mechanism, the machine may be operated at much higher speed than the machines which have heretofore been used.

I have found that the saving in floor space resulting from the lengthwise arrangement 115 of wire bobbins, as indicated above, amounts to as much as 50 per cent., and that the resulting compactness gives a construction of greater rigidity than has heretofore been possible. Also, since the bobbins rotate with 120 the machine, and at a corresponding speed, it is not possible for a wire, if it should break, to catch the frame of the machine and cause breakage of the cradle or other parts.

While I have herein shown and described 125

a preferred embodiment of my invention, it is to be understood that numerous changes may be made therein, and I therefore desire that no limitations be imposed upon my invention except such as are indicated in the appended claims.

What I claim is:

1. In a machine for making wire rope, the combination of a rotatable frame consisting of a plurality of circular spiders connected by means of longitudinal rods, and bearings carried by the said spiders for supporting wire-carrying bobbins co-axially with the said frame and separately removable therefrom.
2. In a machine for making wire rope, the combination of a rotatable frame consisting of a plurality of circular spiders connected by means of longitudinal rods, bearings carried by the said spiders for supporting wire-carrying bobbins co-axially with the said frame, and separately removable therefrom and a sheave carried by one of the said longitudinal rods adjacent to each of the said bobbins.
3. In a machine for making wire ropes, the combination of a rotatable frame comprising a plurality of circular spiders, anti-friction rollers for supporting the said spiders, lon-

gitudinal rods connecting the said spiders, 30 bearings carried by the said spiders for supporting a plurality of wire-carrying bobbins co-axially with the said frame and separately removable therefrom, keys for releasably securing the said bobbins in place, and 35 a sheave carried by one of the said longitudinal rods adjacent to each of the said bobbins.

4. In a machine for making wire rope the combination of a rotatable frame comprising 40 a plurality of circular spiders, a plurality of standards, anti-friction rollers carried by the said standards and supporting the said spiders, anti-friction rollers engaging above certain of the said spiders, longitudinal rods 45 connecting the said spiders, bearings carried by the said spiders, shafts having squared ends received in the said bearings, slideable keys adjacent to the said bearings for holding the said shafts in place, and 50 spring-pressed means for positioning the said keys.

In testimony whereof I the said ALBIN E. ANDERSON, have hereunto set my hand.

ALBIN E. ANDERSON.
